MACHINE FOR MAKING FOAMED PLASTICS OR THE LIKE

Austin Cole III, Redondo Beach, Calif., assignor to
United Process Machinery Co., a corporation of California

Filed Feb. 28, 1961, Ser. No. 64,096

Term of patent 7 years

(Cl. D55—1)

FIG. 1.

FIG. 2.

FIG. 3.

FIG. 4.

FIG. 5.

FIGURE 1 is a perspective view of a machine for making foamed plastics or the like showing my new design;

FIGURE 2 is a side elevational view thereof illustrating the side opposite to that shown in the perspective view of FIGURE 1;

FIGURE 3 is a front elevational view thereof;

FIGURE 4 is a top plan view thereof; and

FIGURE 5 is a rear elevational view thereof.

It is to be understood that the ventilation holes shown fragmentarily completely cover the upper rear panel of the machine.

The dominant features of my design reside in the portion shown in solid lines.

The electrical cord shown in broken lines is either omitted or shown fragmentarily in FIGS. 1, 3, 4 and 5 for the convenience of illustration.

I claim:

The ornamental design for a machine for making foamed plastics or the like, substantially as shown and described.
